UNITED STATES PATENT OFFICE.

ARTHUR E. PEW, JR., OF BRYN MAWR, AND HENRY THOMAS, OF RIDLEY PARK, PENNSYLVANIA, ASSIGNORS TO SUN OIL COMPANY, OF PHILADELPHIA, PENNSYLVANIA, A CORPORATION OF NEW JERSEY.

APPARATUS FOR COMPLETELY SEPARATING GASOLINE FROM MINERAL OIL.

Application filed February 23, 1924. Serial No. 694,475.

The object of our invention is to effect a substantially complete separation of gasoline from mineral oil.

In an application filed of even date herewith, Serial No. 694,470 (Case 1) there is described a process wherein the lighter fractions of gasoline are first distilled off at a relatively low temperature and the heavier residual oil conveyed to a still and therein caused to flow over a surface of large area in a thin layer. The temperature of the still is substantially above the temperature of the first distillation and sufficiently high to vaporize all the heavier fractions of gasoline in said flowing shallow stream. The vapors are conducted to a fractionator, wherein the gasoline constituent thereof is allowed to pass off through a reflux condenser, while the condensate, which is mainly or wholly "gas oil", is allowed to flow to storage. The residual oil from the still is utilized to preheat the crude oil to the degree required to effect the first distillation.

It is well known that in the processes of distillation more commonly used, there is a very incomplete separation of gasoline. If the temperature of distillation is such as to distill off the gasoline completely, an objectionable proportion of higher boiling point constituents goes off with the gasoline. Usually, therefore, distillation is conducted at a temperature that will not carry off an objectionably large proportion of such higher boiling point constituents, with the result that a substantial proportion of gasoline remains in the still. However, in the process set forth in our said application, it is possible to evaporate off substantially all the gasoline while it is flowing over the said extended surface in a thin layer, so that practically no gasoline at all enters the body of oil in the still. At the same time, the still temperature need not be so high as to carry off to the fractionator an objectionably large proportion of higher boiling point constituents.

The present invention comprises the construction of that part of the apparatus whereby the above result is secured. More specifically, it comprises the evaporating pans, constructed and positioned as described and illustrated in said application, over which

the preheated oil is caused to flow in a thin layer, as stated.

A preferred embodiment of the invention is shown in the accompanying drawings, in which—

Fig. 1 is a simplified view of a still with evaporating pans positioned therein.

Fig. 2 is a detail longitudinal sectional view of the upper and oil-receiving end of the upper pan.

Fig. 3 is an end view of Fig. 2.

Fig. 4 is an enlarged section on the line 4—4 of Fig. 1.

a represents a cylindrical-shaped still of any suitable type, adapted to be heated in any suitable manner.

Within the still, and above the level of oil intended to be maintained therein, are pans *b*, *c* and *d*. The upper pan *b* extends lengthwise of the still and is slightly inclined in the direction of its length. The pan is flanged along opposite side edges. These side flanges *e* are of just sufficient height to prevent oil flowing off the pan sidewise. At the rear, or higher, end of the pan, it is provided with an end wall *f*, and a short distance in front of this rear wall is a lateral partition *g*, functioning as a weir, the latter being notched along its upper edge. There is thus formed, between the rear wall *f* and partition *g* a receiving cup *h*. Oil overflows therefrom, in a number of fine streams, through the recesses formed by the notches in partition *g*.

Preheated oil is supplied to the feed cup *h* through the pipe *j*, which, preferably, extends through almost the entire length of the still, so that the oil flowing therethrough absorbs some additional heat before it is discharged into the feed cup *h*.

At the front, or lower, end of pan *b* the oil discharges into a transverse pipe *k*. This pipe, throughout that part of its length underlying the pan, is cut away along its top at a slight angle to its axis, this cut-away part registering with a transverse slot near the front edge of the pan. Opposite ends of the pipe are bent down and discharge into feed cups *m* and *n* at the upper ends of pans *c* and *d* respectively. To insure that approximately equal volumes of oil flowing along pan *b* shall discharge onto the pans *c*—*d*, the pan *b* is provided with a par-

tion *i* extending longitudinally from the weir *g* to the pipe *k*. The notched weir *g* insures a practically equal division of oil from the feed cup between the parts of the 5 pan *b* on opposite sides of the partition *i*.

Each lower pan *c*, *d*, is constructed like the upper pan *b*; but its inclination is opposite that of pan *b* and its width is less, although it is preferred that the combined widths of 10 pans *c* and *d* shall exceed the width of pan *b*.

The still is provided with a draw-off pipe *o*, through which the oil is pumped from the still at such rate as will maintain the desired level of oil in the still. *p* is a vapor outlet to 15 a fractionator.

Oil entering the still through pipe *j* discharges into the receiving cup *h* near one end of the still, overflows over the notched weir *g* and, spreading out over the surface of 20 pan *b*, flows along the same toward the opposite end of the still. The depth of this flowing stream may be regulated as desired, such depth depending on the rate of inflow of the oil, the degree of inclination of the 25 pan, and the width of the pan. Oil discharges from this pan through pipe *k* onto pans *c* and *d*, down which it flows in a direction opposite to that of the stream flowing along pan *b*. At the lower ends of the pans 30 *c* and *d*, the unvaporized oil discharges into the body of the still.

It is found that, by the use of this contrivance, if the still temperature is approximately the usual distilling temperature (say 35 520° F.) required in the more commonly used processes for separating gasoline, substantially all the gasoline will be vaporized. Indeed, an analysis of the residual oil pumped from the body of the still discloses 40 practically no trace of gasoline.

The effectiveness of the contrivance is believed due to the following factors: The oil spreads out over a large surface in a thin layer, thereby allowing more intimate contact therewith of the hot vapors. Further, this thin sheet of oil is in contact throughout its area with hot metal, between which and the oil there is a rapid exchange of heat. It is somewhat advantageous to have the 45 lower pans of greater combined width than the upper pans, so that the lower streams of flowing oil are shallower than the upper stream; the lower pans presenting conditions favorable to the vaporization of the heavier 50 fractions of gasoline that may have escaped vaporization on the upper pan. However, the number of tiers of pans, and the width and arrangement of pans, are susceptible of considerable variation and still embody our 55 invention.

Having now fully described our invention, what we claim and desire to protect by Letters Patent is:

1. In an apparatus for effecting a substantially complete separation of gasoline 60

from mineral oil, a still comprising an elongated container adapted to hold a substantial body of oil, means to receive and laterally distribute oil in the upper part of the container, an oil conveyor comprising a succession of inclined pans arranged in the upper part of the container and down which the oil admitted to the container is adapted to successively flow in a relatively thin layer and discharge into the oil body, and means 70 insuring the maintenance of an equal volume of oil on opposite sides of the longitudinal central part of the upper pan and insuring the equal lateral distribution of oil from the upper pan to the part of the oil conveyor immediately beneath it. 80

2. In an apparatus for effecting a substantially complete separation of gasoline from mineral oil, a still comprising an elongated container adapted to hold a substantial body of oil, means to receive and laterally distribute oil in the upper part of the container, a flat upper pan slightly inclined in the direction of its length and the higher end of which is adapted to receive said oil, a plurality of lower pans arranged side by side under the upper pan and slightly inclined in a direction opposite to the direction of inclination of the upper pan, and means to distribute oil discharged from the upper pan 90 in substantially equal volumes to the lower pans. 95

3. In an apparatus for effecting a substantially complete separation of gasoline from mineral oil, a still comprising an elongated container adapted to hold a substantial body of oil, means to receive and laterally distribute oil in the upper part of the container, a flat upper pan slightly inclined in the direction of its length and the higher end of which is adapted to receive said oil, a partition extending along approximately the longitudinal center line of the upper pan, two lower pans arranged side by side under the upper pan and on opposite sides of said line and slightly inclined in a direction opposite to the direction of inclination of the upper pan, and means to convey the several streams of oil from the lower end of the upper pan to and distribute them across the higher ends of the lower pans. 110 115

4. In an apparatus for effecting a substantially complete separation of gasoline from mineral oil, a still comprising an elongated container adapted to hold a substantial body of oil, means to receive and laterally distribute oil in the upper part of the container, a flat upper pan slightly inclined in the direction of its length and the higher 120 end of which is adapted to receive said oil, a plurality of lower pans arranged side by side under the upper pan and slightly inclined in a direction opposite to the direction of inclination of the upper pan, and 125 130

a pipe extending across the lower end of the upper pan, said pipe cut away to receive oil from the upper pan, opposite ends of the pipe being down-turned and adapted to convey oil to the upper ends of the respective lower pans.

5. In an apparatus for effecting a substantially complete separation of gasoline from mineral oil, a still comprising an elongated container adapted to hold a substantial body of oil, means to receive and laterally distribute oil in the upper part of the container, a flat upper pan slightly inclined in the direction of its length and the higher end of which is adapted to receive said oil, a plurality of lower pans arranged side by

side under the upper pan and slightly inclined in a direction opposite to the direction of inclination of the upper pan, and means to distribute oil discharged from the lower pan to the higher ends of the lower pans, the combined widths of the lower pans being greater than the width of the upper pan to provide relatively shallower streams, thereby effecting vaporization on the lower pans of heavy gasoline fractions that have escaped vaporization on the upper pan.

In testimony of which invention, we have hereunto set our hands, at Philadelphia, Pa., on this 14th day of February, 1924.

ARTHUR E. PEW, JR.
HENRY THOMAS.
